UNITED STATES PATENT OFFICE.

WILHELM MAUSS, OF JOHANNESBURG, TRANSVAAL, SOUTH AFRICA.

CENTRIFUGAL SEPARATOR.

1,111,600.

Specification of Letters Patent. Patented Sept. 22, 1914.

Application filed December 17, 1912. Serial No. 737,171.

To all whom it may concern:

Be it known that I, WILHELM MAUSS, a British subject, residing at Commercial Exchange Buildings, Johannesburg, in the 5 Province of the Transvaal, Union of South Africa, have invented certain new and useful Improvements in Centrifugal Separators, of which the following is a specification.

10 The present invention relates to centrifugal separators of that kind wherein the material to be separated is fed into a drum which is rotated about an axis distant from its own axis in order to effect the separation of the constituents of the material and is also rotated at a relatively slow rate about its own axis. The effect of the latter rotation is so to change the position of the 15 surface upon which the separated material 20 of higher specific gravity is deposited as to diminish or reverse the effect of the centrifugal force in holding the deposited material on the surface of the drum and thus enable such material to be readily separated 25 therefrom. The apparatus usually consists of two or more vessels symmetrically disposed about the main axis of rotation.

It is the purpose of the present invention to provide in such apparatus an improved 30 form of drum specially adapted to clear itself readily.

In the accompanying drawing: Figure I is a partly sectional elevation of a centrifugal apparatus embodying the improvements. Fig. II is an ideal section on A—A, 35 Fig. I.

1 is a main shaft rotated about its axis 2 by suitable driving means 3, 4, and having rigidly secured to it a cradle 5. Said cradle 40 carries two or more drums 6 symmetrically disposed to it and having their axes 7 spaced from axis 2 so that upon rotation of shaft 1 they are whirled bodily around the same.

Each drum is mounted in the cradle 5 to 45 be rotatable about its own axis 7 and is so rotated by means of gearing 8, shaft 9 passing through shaft 1, pinion 10 thereon and the annular racks 11 on the outside of the drums. Shaft 1 is bifurcated at 12 to permit the engagement of said pinion 10 with the racks 11. Each drum is served by a feed pipe 18 extending from a common trough 19 mounted upon and rotating with shaft 1. Each drum consists of a lower conical main 55 portion 24 which converges toward the completely open lower end 16. At its upper end

is an inwardly projecting flange 13 forming the overflow lip. The axis 7 of the drum is inclined upwardly away from the main axis 2; the disposition of the parts being such that the portion 15 of the wall nearest the main axis 2 stands substantially vertically, while the outermost point 25 of the lower edge of the drum is almost vertically below the outermost point 26 of the overflow lip 13, but slightly nearer to axis 2 than the latter, thus forming a chamber 27 to contain the material during separation. The inclination of the outermost portion 28 of the wall of the drum is such that the material 70 tends to slide off the same when the apparatus is at rest.

A drum as above described provides at its outermost part the separating chamber 27 such as to retain the material in it against the action of gravity, while allowing the liquid constituent of the material to flow away over the lip 13. On the other hand, the chamber characteristic disappears entirely at that part 15 of the drum next to the main 80 axis 2, which part 15 becomes simply a vertical wall from which the material may fall freely through the completely open lower end of the drum. Moreover, in the event of the machine stopping this form of drum enables the whole of its contents to fall out freely from all parts of its periphery. Below the drums is the bin 17 for receiving the heavy separated material.

20 is an annular casing inclosing the cradle and drums to reduce air friction and form a shield in case of breakage.

The operation of the device is as follows. The apparatus having been brought up to normal speed, the mixed material, which 95 may be supposed to be unclassified ore pulp and cyanid solution, is passed from trough 19 and pipes 18 into the chambers 27 of the drums. Here the centrifugal force causes the pulp 22 to segregate from the liquid 21 and to settle on the wall of the drum, while the liquid 21 flows off over the overflow lip 13 to a receiver 14. The deposited pulp is carried around with the drum as the latter rotates on its axis 7 (in the direction of the arrow, Fig. II), thus causing the pulp to emerge from the layer of liquid and at the same time progressively reversing the relative positions of said pulp and said surface in regard to the main axis of rotation 110 2. The effect of the centrifugal force in holding the material to said surface is thus

gradually diminished until it disappears when said surface is radial to axis 2 whereafter the effect is reversed and the material, if it has not already fallen off by gravity, 5 is projected from the surface by an increasingly effective force which reaches its maximum at the position 15. Upon stoppage of the apparatus, the whole of the drum's contents fall out, leaving the machine ready to start without having first to be cleared of settled pulp, as is frequently necessary in centrifugal apparatus. In some cases it may be desirable to provide the inner surface of the drums with ribs 10 15 23 (Fig. I) which positively convey the settled material around with the drum.

What I claim and desire to secure by Letters Patent is:

Centrifugal separating apparatus comprising a drum rotatable about a main axis 20

distant from its own axis and also rotatable about its own axis, said drum consisting of a lower conical main portion converging toward its open lower end and an inwardly projecting flange at the top, the axis of the 25 drum being so inclined away from the main axis upwardly that the portion of the drum remote from the main axis forms a separating chamber in which material is retained centrifugally against the action of gravity, 30 while the portion of the drum next to the main axis forms a substantially vertical wall from which material can fall through the lower end of the drum.

In testimony whereof I affix my signature 35 in presence of two witnesses.

WILHELM MAUSS.
